UNITED STATES PATENT OFFICE.

WALTER G. HORSTMAN, OF LACONA, IOWA.

DESIGN FOR AN AUTOMOBILE FOOT-SCRAPER.

56,432.

Specification for Design.

Patented Oct. 26, 1920.

Application filed January 2, 1920. Serial No. 349,026. Term of patent 14 years.

To all whom it may concern:

Be it known that I, WALTER G. HORSTMAN, a citizen of the United States, and a resident of Lacona, in the county of Warren and State of Iowa, have invented a certain new, original, and ornamental Design for an Automobile Foot-Scraper, of which the following is a specification, reference being had to the accompanying drawing, forming part thereof.

Figure 1 shows a front elevation of an automobile foot scraper embodying my invention.

Fig. 2 shows a top or plan view of the same.

Fig. 3 shows an end elevation of the device, and

Fig. 4 shows a sectional view taken on the line 4—4 of Fig. 3.

Fig. 5 shows an enlarged perspective view of my device.

I claim:

The ornamental design for an automobile foot scraper, as shown.

Des Moines, Iowa, December 10, 1919.

WALTER G. HORSTMAN.
